The ornamental design for a segment of a cover for a sports ball, as shown and described.

DESCRIPTION

FIG. 1 is a perspective view showing my new design for a segment of a cover for a sports ball with the portion shown in broken lines being for illustrative purposes only and not forming any part of the design; FIG. 2 is a front view thereof, the back view being plane and unornamented; and, FIG. 3 is a side view thereof with the opposite side being identical.

FIG. 3
